(57) **CLAIM**

The ornamental design for a traction band, as shown and described.

DESCRIPTION

FIG. 1 is a front left perspective view of the exterior of the traction band;

FIG. 2 is a front right perspective view of the interior of the traction band;

FIG. 3 is a front right perspective view of the exterior of the traction band;

FIG. 4 is a front left perspective view of the interior of the traction band;

FIG. 5 is a plan view of the exterior of the traction band;

FIG. 6 is a plan view of the interior of the traction band;

FIG. 7 is a left side view of the traction band;

FIG. 8 is a right side view of the traction band;

FIG. 9 is a front view of the traction band;

FIG. 10 is a rear left perspective view of the exterior of the traction band;

FIG. 11 is a rear right perspective view of the interior of the traction band;

FIG. 12 is a rear right perspective view of the exterior of the traction band; and,

FIG. 13 is a rear left perspective view of the interior of the traction band.

The broken line portion in FIGS. 5, 6, 7, and 8 is included for purpose of illustrating that a specific length of traction band forms no part of the claimed design.
